UNITED STATES PATENT OFFICE.

BURT F. DAVIS, OF JACKSON, OHIO, ASSIGNOR TO LOUIS H. HOLLBERG, OF JACKSON,
OHIO.

LEVEL.

1,023,301.

Specification of Letters Patent. Patented Apr. 16, 1912.

Application filed December 18, 1911. Serial No. 666,379.

To all whom it may concern:

Be it known that I, BURT F. DAVIS, a citizen of the United States, residing at Jackson, in the county of Jackson and State of 5 Ohio, have invented certain new and useful Improvements in Levels; and I do declare the following to be a full, clear, and exact description of the invention, such as will enable others skilled in the art to which it applies 10 to make and use the same.

This invention relates to measuring instruments, and more especially to levels; and the object of the same is to produce an instrument of this character by means of 15 which a horizontal or any desired angle thereto can be instantly found and accurately determined without the necessity for employing the usual closed tube of glass, commonly found in spirit levels. This and other 20 objects are accomplished by the construction described in the following specification and illustrated in the drawings wherein—

Figure 1 is a side elevation of this level complete. Fig. 2 is a side elevation of the 25 metal portion thereof removed from the stock and with the nearer face plate of glass removed, the weight in this view being tilted so that the two hands are not in alinement. Fig. 3 is a central vertical longitudinal section view, and Fig. 4 is a cross section on the line 4—4 of Fig. 3.

In the drawings the letter W designates the stock or body which is usually of wood and stands horizontal when this device is to 35 be used for a level or vertical when it is to be used as a plumb, and through a transverse hole at about the center of the length of this wooden member passes a metallic member M fitting tightly in said hole and 40 made in the shape of an open-ended cylinder whose extremities are covered by glass disks G which are preferably ground or rendered otherwise opaque excepting for a clear space C at the center; and between 45 said panes or disks G and within the cylinder M is located the leveling mechanism proper.

Coming now more particularly to the 50 details of the present invention, the numeral 1 designates a ring fitting closely but revolvably within the cylinder M and preferably having on its side edges about four marks 2 set quartering to each other and which move adjacent a graduated scale 3 55 inscribed on each edge of the metallic cylin-

der M. Pivoted at 4 in the latter is the eccentric head 5 of a brake or check whose shaft carries a thumb piece or latch 6 at one extremity moving over the face of the stock W whereby the head 5 may be turned to 60 throw it into contact with the exterior of the ring 1 when any mark 2 on the latter stands opposite a graduation on the scale 3 as desired. I describe this type of brake or check, but any other form of the same may be employed. At diametrically opposite points within the ring 1 are eyes 7 in which are pivoted the outer ends of two hands 8 which extend normally toward each other and have arrow heads 9 at their inner ends as seen, 70 and the bodies of these hands have longitudinal slots 10 by means of which they are swung around their pivots 7. It is obvious that when the extremities of the heads 9 stand in true alinement as seen in Fig. 1, a 75 true horizontal would be designated by the marks 2 at the right and left of the ring 1 and if the same were in register with the proper marks on the scale 3 the device would become a level; whereas, by turning the 80 stock 90° so that the lateral marks 2 on the ring register with other indications on the scale 3 quartering to those just described, the device becomes a plumb, and at points between these extremes the body may be 85 used to find any desired angle.

The means for oscillating the hands on their pivots 7 consist of a weight preferably having a curved or arcuate lower end 11 standing within the ring 1 and from whose center rises an upright shank 12 having a triangular transverse eye 13 through it, and from opposite sides of said shank project arms 14 whose extremities are upturned and forked as shown at 15, and the arms of each 95 fork are connected by a transverse pin 16 which moves loosely in one of the slots 10. This weight is supported upon a knife edge 17 extending transversely through said triangular eye 13 and having lugs 18 rising at 100 either side of the same, and such knife edge fulcrum is mounted or carried at the upper end of a standard 19 whose foot 20 is secured within the ring 1. The parts are by preference entirely of metal, excepting the 105 glass disks and the wooden stock, although the exact metal used and the proportions and the shapes of the various elements are not essential to the successful operation of the device.

In use it may be assumed that the parts stand as seen in Fig. 1 with the marks 2 on the ring 1 opposite the quarter marks in the scale 3 so that one of said marks 2 is opposite zero as seen. The operator places the stock upon some object that is supposed to be level, and gravity causes the shank of the weight 11 to hang vertically beneath the knife-edged fulcrum 17 so that its arms 14 stand horizontal and the pins 16 through their forks cause the two hands 8 to stand truly horizontal with the points of their heads 9 in exact alinement or register as seen in Fig. 1; and thus the device is used as a level and will find a horizontal with extreme accuracy. If the object thus tested is not horizontal and the weight swings a little to one side of a vertical, one pin 16 will be raised and the other depressed and one hand thereby raised around its pivot 7 and the other depressed, and as the slots 10 are relatively nearer to said pivots 7 than they are to the points of the heads 9, the slight movement of the weight will be amplified into a considerable movement of the arrow heads so that the fact that they do not accurately register will be readily observable through the glass. The construction therefore renders the instrument extremely delicate, and the purpose of carrying the arms 14 laterally out from the shank 12 and locating the pins 16 near the pivots 7 is obvious. Supposing now that the operator desires to ascertain a vertical or plumb line, he has but to throw off the brake which is accomplished by moving the finger or hand piece 6 so that the eccentric head no longer engages the ring 1, and when he turns the stock W upright the weight will carry the entire ring 1 around within the cylindrical member M until one of the scale marks 2 has moved 90° over the scale 3. The brake or check is then reapplied to hold the ring 1 in this adjusted position, and the action of the movable parts is as above described.

What is claimed as new is;

1. In an instrument of the class described, the combination with a stock, an open-ended cylinder passing through the body of the stock and having scales inscribed on its extremities, and a brake device within the wall of the cylinder; of a ring mounted loosely within said cylinder and having marks quartering to each other on both extremities, glass disks over said extremities, two hands pivoted at their outer extremities within said ring on a true diameter thereof;

and a pendulum connected with the hands and adapted to bring their inner extremities in register.

2. In an instrument of the class described, the combination with a stock, an open-ended cylinder passing through the body of the stock and having scales inscribed on its extremities, and a brake device within said cylinder consisting of a shaft rotatably mounted in its wall parallel with its axis, an eccentric head secured upon the inner end of said shaft, and a thumb-piece on its outer end; of a ring mounted loosely within said cylinder and having marks on its extremities, two hands pivoted at their outer extremities within said ring on a true diameter thereof, and a pendulum connected with the hands and bringing their inner extremities into register when their pivots stand in a horizontal plane.

3. In a level, the combination with a stock having a transverse opening, a ring therein having eyes at diametrically opposite points, and two hands whereof each has its outer extremity pivoted in one of said eyes, its body provided with a longitudinal slot adjacent said pivot, and its inner end pointed; of a weight pivotally supported within said ring and having arms diverging laterally from the pivot and forked, and a pin through the fork of each arm and loosely engaging in one of said slots.

4. In a level, the combination with a stock having a transverse circular opening, a ring mounted therein and having pivots at diametrically opposite points, and two hands whereof each has its outer extremity mounted on one of said pivots, its body provided with a longitudinal slot adjacent said pivot, and its inner end pointed; of a standard rising from the bottom of said ring and having a knife edge at its upper end with two lugs rising from the edge thereof, a weight having a heavy arcuate lower end, an upright shank pierced with a triangular eye hung on said knife edge between the lugs, and two horizontal arms having their outer ends upturned and forked, and a pin through each fork and loosely engaging in one of said slots.

In testimony whereof I have hereunto set my hand in presence of two subscribing witnesses.

BURT F. DAVIS.
